NONSKID SHOE CLAMP

Arthur E. Seaton and Charles E. Tunks,
Portland, Oreg.Application July 27, 1936, Serial No. 92,852
Renewed March 31, 1938

1 Claim. (Cl. 36—64)

This invention relates to non-skid shoe clamps and is particularly adapted to golf players, climbers, icy conditions, in fact any place where it is desired to keep the shoe from slipping over the 5 surface to be traversed.

The primary object of this invention is to construct a clamp that requires no additional adjustment after it is once adjusted to any one particular shoe.

10 Another object of the invention is to make a clamp without any moving parts to get out of adjustment.

A still further object of the invention is to provide a clamp made up of but two stampings, making it economical to manufacture.

15 These and other incidental objects will be apparent in the following specification, drawing and claim.

Referring to the drawing:

20 Figure 1 is a plan view of the under side of a shoe, having one of the new and improved clamps fixed thereon.

Figure 2 is a perspective bottom plan view of a shoe, showing one of the clamps partially 25 clamped thereon, illustrating the method of locking the clamp on the shoe.

Figure 3 is a perspective view of the assembled device.

30 Figure 4 is a perspective underneath view of the main body portion of the clamp.

Figure 5 is a perspective view of the clamp used in connection with the main body portion of the non-skid clamp for locking the same on the sole of the shoe.

35 In the drawing:

1 is an underside view of the sole of a shoe. 2 is the main body portion of the non-skid clamp having upturned clamps 3 and 4 for fitting over the edge of the sole. The clamp is forced onto the sole from the toe portion. The upper part of the clamping locks 3 and 4 are turned inwardly at 5 for the purpose of gripping the upper surface of the sole. The non-skid calks 6, of the usual type, are fixed into the body portion 2, or these non-skids may be stamped out of the main body 2 forming projections.

The main body portion 2 is held in place by the locking bar 8, which is made from spring steel. The locking bar 8 is shaped as shown in Figure 50 5, tending to hold itself towards the sole of the

shoe through the action of the clamping bolt 9 and lock nut 10. The clamp has a slot 11 for coacting with the locking bolt 9 for different adjustments conforming to the different shape or size soles. Projections 12 are stamped upwardly forming a rough surface on the underneath side of the clamp for engaging the body portion 2. The purpose of these projections is to assist in the holding of the clamp 8 in a fixed position, relative to the main body portion. A 10 right angle bend 13 is formed on the opposite end of the bar for engaging the edge of the sole. The locking bolt 9 has a countersunk head 14 for engaging the body portion of the clamp.

15 After this non-skid clamp is adjusted to the particular shoe, that is to be worn, all that is necessary to apply the clamp is to force the main body portion of the clamp from the front or toe end of the sole and rearwardly until the clamps 3 and 4 snugly engage with the edge of the sole, when the free end of the locking bar 8 may be forced over the edge of the sole at 15. In order to remove the clamp an outward turn of the projection 16 on the locking bar enables the wearer to force the free end of the bar away 20 from the sole and remove the clamp by pushing the same forward and off the front end of the sole.

25 Having described our invention as shown, we do not wish to be limited to this particular form 30 of construction, as other forms of embodiment may be found practical still coming within the scope of the claim to follow.

What is claimed is:

A creeper comprising a main plate of a single 35 integral formation having its ends turned upwardly to form hooks to engage the edges of a shoe sole, non-skid projections extending from the main plate, a single resilient locking bar formed at its rear free end with a hook to engage the edge of a shoe sole in rear of the maximum width thereof, the locking bar being formed with a slot near its forward end to engage a threaded pin depending from the main plate, a lock nut engaging the pin below the locking bar, 40 the locking bar being formed on its upper surface with a roughened surface to bear upon the under surface of the main plate on the tightening of the lock nut.
